CLAIM

The ornamental design for a vehicle tire, as shown and described.

DESCRIPTION

FIG. 1 is a perspective view of a vehicle tire showing our new design, it being understood that the tread pattern is repeated uniformly throughout the circumference thereof;

FIG. 2 is a front view of the tire of FIG. 1 it being understood that the back view is the same; and, FIG. 3 is a side view of the tire of FIG. 1 it being understood that the other side is the same.

FIG. 1

FIG. 2

FIG. 3
